UNITED STATES PATENT OFFICE.

ERASTUS E. PIERCE, OF NEW BRIGHTON, PENNSYLVANIA, ASSIGNOR OF
ONE-HALF TO CHARLES M. MERRICK, OF SAME PLACE.

MACHINE FOR MAKING HORSESHOE-NAILS.

SPECIFICATION forming part of Letters Patent No. 241,562, dated May 17, 1881.

Application filed November 5, 1880. (Model.)

To all whom it may concern:

Be it known that I, ERASTUS E. PIERCE, of New Brighton, Beaver county, Pennsylvania, have invented certain Improvements in the Manufacture of Horseshoe-Nails, of which the following is the specification.

My invention relates to the manufacture of horseshoe-nails by what is known as "forging"—that is, by gradually reducing a nail-rod to the required shape; and my invention consists in the mode and means hereinafter set forth, whereby the end of a stationary rod is rapidly formed into the shape of a finished nail, bevel-pointed, ready to drive, or into a nail-blank to be finished by a subsequent operation, and the finished nail or blank then detached from the rod.

The special objects of my invention are to rapidly forge the blanks, or produce nails of uniform size, length, and shape, with compact and well-finished points, and to prevent the heating and wear of the dies and consequent variation in size of the nails, and to avoid the necessity of frequently renewing the dies.

In the drawings, Figures 1 to 6, inclusive, are views illustrating the progressive formation of the nails by reducing the end of the rod. Fig. 7 is a transverse sectional elevation of part of a machine used in carrying out my invention. Fig. 8 is a side elevation, partly in section, of part of the machine. Fig. 9 is a plan view of Fig. 8. Fig. 10 is a plan view showing a pair of roller-dies. Fig. 11 is an elevation of Fig. 10. Fig. 12 is a side view, and Fig. 13 an end view, of one of the pointing-dies, and Fig. 14 a side view of one pair of the beveling-dies.

Heretofore in the forging of horseshoe-nails it has been customary to form the nail from the end of a rod by means of four hammers, or by hammers, dies, or rollers, or combinations of the same, operating in connection with a stationary anvil upon which the end of the rod is rested. Among the many objections to these modes of manufacture are, first, the difficulty or impossibility of properly finishing the points of the nails; second, the rapid heating of the anvil, hammers, &c., by reason of being brought in repeated contact with each nail and

consequent rapid wear of the same, resulting 50 in irregularity in the product of the machine; third, the destructive results of the percussive action of the hammers, dies, &c., and springing of the frame under varying pressures; fourth, the variation in the size of the nails, owing to 55 the contraction and expansion both of the frame and working parts of such machines.

Overcome these objections and secure many attendant advantages by operating upon the end of a stationary bar or rod by means of 60 traveling or rolling dies acting upon all four sides of the rod, gradually reducing it to the required shape without any prolonged or repeated contact of the hot rod with any one die, so that the dies do not heat and wear away as 65 heretofore. The force of the blow is absorbed in the shaping of the metal, and not conveyed to the frame to rack the latter, while all the faces of the nail can be operated upon in quick succession, so as to impart with rapidity and 70 precision any form required.

One of the greatest difficulties in the forging of horseshoe-nails has resulted from the irregularity in the size of the nail-rod and the difficulty of maintaining it uniformly heated, so 75 that, however perfectly the same may be fed, the nails produced are of irregular sizes, the points of many being imperfect and ragged.

I discard the idea of attempting to regulate the size of the nail by graduating the amount 80 of stock presented, but secure the desired result by presenting in all cases at least as much stock as will suffice to make a blank equal in length to the finished nail, and after the formation of the blank, cutting off the end of the 85 same so as to leave it a little shorter than the finished nail, and always exactly of the required length, and then subjecting the same to the action of the pointing and beveling dies, which are constructed to slightly elongate, condense, reduce, and form the point to the proper shape, and produce unvarying results.

Different appliances may be employed for carrying out these operations. In the drawings I have illustrated and will now proceed to 95 describe such as I have found very effective.

The rod X, from which the nails are to be made, is heated by means of a furnace through

which it travels, or in any other suitable manner, and is then placed in such a position, and there held, that while stationary, its end will be successively operated upon by roller-dies 5 properly constructed, arranged upon and carried by a suitable frame so as to move past and shape each face and side of the rod. Thus successive rotating dies $a' a^2$, &c., are carried over and act upon the upper side or face of the 10 rod, which is gradually reduced and shaped between such dies and lower dies, i , which support and traverse the rod below, while side dies, $b' b^2 b^3$, &c., arranged in pairs, alternate in action with the upper and lower dies and 15 successively traverse the sides of the rod and co-operate with the other dies to elongate and form the reduced body or shank and head of the nail, and taper the sides of the shank near the end thereof. The action of each pair of 20 roller-dies is illustrated by that of the dies b^{10} b^{11} (shown in plan, Fig. 10) in the act of traversing the sides of the end of the rod X held stationary between them, the action of the rolls, as they revolve and travel in the direction of the 25 arrows along the rod, being precisely the same as if the rod were passed between the rolls turning in stationary bearings, the metal being rolled, consolidated, and formed into shape with great rapidity and precision, but without 30 any lengthened contact with the rolls, which do not become so heated and do not wear away with such rapidity as do reciprocating dies. In the first instance the bar is fed forward to such 35 an extent that the action of the dies, even with a minimum amount of metal at the lowest heat will produce a blank at least equal in length to the nail required, as shown in Figs. 1 and 2, the dies $c' c'$ then cutting off any surplus metal on the line x , Fig. 1. The solid end thus insured is acted on successively by pairs of side 40 pointing-dies, $d' d'$, alternating with the upper and lower beveling-dies, $e f i$, slightly elongating, reducing, and forming the point to the proper shape, as shown in Figs. 3 and 4. The 45 dies $f i$ are followed by rolls $g' g'$, which straighten the nail, thus bringing it to the form shown in Figs. 5 and 6 by one continuous series of operations without moving the rod, from which the nail is then severed on the line y , Fig. 3, 50 by cutters $h' h'$, hereinafter more fully described.

By the mode of operation above described I overcome the objections incident to the modes heretofore in use, where stationary anvil dies or hammers are employed, which come in repeated contact with each nail throughout its entire length, the consequence being the reduction of temperature of the rod and the transfer of the heat to the working parts of the machine, causing the expansion and contraction previously noted.

I have not as yet described nor do I confine myself to the use of any special means for carrying and driving the roller-dies, as various modes may be adopted. They may be mounted 65 in bearings on straight slides, and driven by gears, cams, or flexible shafts; or they may be arranged upon four converging disks, rotated

simultaneously to bring the rollers successively into operation upon the stationary bar, the rollers being rotated positively and independently of the disks by cams or gears, so as to bring the working-surfaces to the proper positions on the rod; or, as shown in the drawings, they may be all carried by a single circular disk or frame, A, mounted upon a shaft, B, turning in bearings of a frame, C, suitably supported. The frame A is pierced radially to receive the shafts 4 4 of the roller-dies $b' b^2$, &c., $d' d'$, &c., and transversely for the shafts 5 5 of the roller-dies $a' c' e' f' g' h'$, &c. The radial shafts are driven by a stationary gear-disk, E, bolted to the frame C, and having an annular rack, K, on each side, gearing with the pinions m of the shafts on such side; and the transverse shafts are driven by a stationary gear-disk, F, also bolted to the frame C, with the teeth of which engage pinions m' on the ends of said shafts. The shaft of each of the inner rollers, c' , g' , and h' , is geared with and is driven from the shaft of the outer roller. 85 By this arrangement the rotation of the frame A insures the positive rotation of the various roller-dies, cutters, &c., so that each will act in perfect unison with the others. The plain roller-dies i turn on transverse pins b^{18} , extending 90 across an annular recess, Z, of the frame A, the sides of which recess maintain the rollers in place. Said rollers i may or may not be geared with the rolls $a' a'$, &c., in the same manner as $c' g' h'$. As the circular frame A revolves with great rapidity each of the forming and operating appliances will remain in contact with the bar an instant only.

As a rotating cutter fixed to the shaft (like that shown at c) will not cut the head of the nail at the proper angle, I employ the construction shown at $h' h'$, where the cutter-roller h' has a curved slot receiving a curved slide, r , one end of which is sharpened and forms the cutter and the other end is rounded.

Opposite the forward edge of the cutter-roller is a cam-plate, J, so constructed that as the roller revolves in the direction of the arrow and the end of the curved slide r is brought against the plate J the said slide, while being turned backward by the rotation of the roll, will be suddenly thrust outward in a straight path across the space between the rollers $h' h'$, cutting against the edge 6 of the roller h , between which and the roller h' the bar is severed on the line y , Fig. 3. The edge of the cutter is caused to travel in a straight line while severing the nail from the rod by the combined circular movements of the roller h' backward and of the curved cutter-slide forward, the curve of the cutter-slide neutralizing the effect of the backward rotary motion of the cutter-roller h' . The further revolution of the roll carries the blunt end of the cutter-slide away from the cam J when a spring throws it backward.

It may be noted that during the cutting the edge of the cutter and the cutting-edge 6 of the roller h are moving backward relatively to

the carrier-frame A, but are nearly stationary relatively to the rod.

Instead of severing the blank from the rod by a traveling cutter it may be severed by cutters supported by the frame C and brought into operation after the nail-forming devices have moved away from the rod.

As the rollers travel in curved courses, in order to straighten the nail the roller-dies g' g' have curved edges so eccentrically disposed as regards their axes that on the forward travel of the dies from the position shown in Fig. 8 and their revolution in the direction of the arrows the edges of the dies will coincide with a line, 3 3, tangential to the circular path in which the dies travel, thus bringing the nail to coincide with such line and straightening the same. In case of mounting the roller-dies upon four converging disks or on a straight slide the nails would be formed straight, thus dispensing with the straightening device.

The cutters for severing the surplus metal from the end of the nail-blank consist of the roller c' socketed to receive a straight chisel, c², which is retained detachably by a binding-screw, and the roller c, with a cutting-edge, c³, against which the chisel shears the nail.

It will be seen that as the roller-dies are all mounted on a single disk or frame, A, some special mode must be employed to introduce the end of the rod between the coinciding series of dies. To do this I present the rod at an angle to the face of the frame A, as shown in Fig. 9, and tangential to the path of the rollers, as shown in Fig. 8; and such portions of the roller-dies a a' a², &c., and of the outer series of edging-rollers b² b⁴ b⁶, &c., as would, in their rotation, come in contact with the rod at a point back of that portion thereof which is to form the nail are cut away and so formed that they will admit the rod, and only begin to act thereon after the operating-edges are on opposite sides of the bar. One effect of the first pair of rollers, a a', is to bend so much of the rod as is to form the nail into a line parallel to the face of the frame A, in a position above the groove Z, Figs. 1 and 9, prior to beginning the reduction of the rod, after which it will be further acted upon by the succeeding roller-dies brought above, beneath, and at opposite sides, while the remainder of the rod serves merely as a support for the portion acted upon, and is out of the way of the operating devices.

The rod may be guided by a suitable grooved rest, X', and may be presented, fed, and retained by hand or automatically by suitable feed mechanism, care being taken at each feed to present at least so much of the rod as will be sufficient to form a blank equal in length to the completed nail.

As I employ only traveling surfaces the rod maintains its heat for a much greater length of time, as the contact of the rod once during the formation of the nail with each of the roller-dies is for so short a time that the dies do not, except to a very limited extent, become heated,

and reduce the temperature of the rod. For example, supposing the above-described machine to be making one hundred nails per minute for ten hours consecutively, each roller-die would be in contact with the hot rod but twenty minutes during that time.

It will be apparent that the variations which must occur from other modes of operation, owing to differences in the feed, temperature, and size and density of the rod, cannot affect the length or size of the product in this case; also, that the area of the nail will in all cases be the same at any given point, owing, first, to the fact that the roller-dies are all journaled in one solid frame, thereby precluding the possibility of the rollers springing apart; second, the contraction and expansion of the roller-dies are neutralized by the contraction and expansion of the frame A. Thus the space between the peripheries of the roller-dies always remains the same. A further and very important result is the condensing and solidifying of the nail-points, so that a much superior product is secured than by processes where the nail ends are spread and sheared, which operations have often the effect of opening and dividing the fiber so as to form points liable to split.

Where it is not desired to form a completed nail the dies may be so limited in number and so constructed as to form blanks to be completed by a subsequent operation with a finishing-machine.

It is obvious that the same principle of reduction is applicable to the formation of articles other than nails.

I claim—

1. The within-described improvement in the art of making horseshoe-nails, the same consisting in rolling and molding all sides of a stationary bar to form the end into a complete bevel-pointed nail, and then severing the latter from the rod, as set forth.

2. In the manufacture of horseshoe-nails from a bar, the mode described of finishing the nail by rolling the shank on all four sides, cutting off transversely any surplus metal, and then beveling and finishing the point, as set forth.

3. The mode of automatically manufacturing horseshoe-nails, the same consisting in, first, feeding the rod; second, forming the head and shank by rolling on all four sides of the rod, then, third, cutting off any surplus metal at the point; fourth, rolling the end to form a bevel-point, and, fifth, severing the nail from the rod, the whole being accomplished by a series of consecutive operations upon a stationary rod, substantially as set forth.

4. The combination, in a nail-making machine, of series of roller-dies and carrying and driving mechanism, whereby said dies are revolved positively and are brought successively in pairs into operation upon all the opposite faces and sides of a rod, substantially as set forth.

5. The combination, with the series of traveling dies for forming the head and shank of the nail, of cutters for removing the surplus

metal, and dies arranged to operate on all sides of the rod for reducing and shaping the end to form the point, substantially as set forth.

6. The combination, with traveling forming-dies arranged to operate upon all sides of a stationary nail-rod, of dies constructed to straighten the nail, substantially as set forth.

7. The combination, with the traveling forming-dies arranged to operate upon all sides of a stationary rod, of dies constructed to straighten the nail, and cutters for severing the nail from the rod, substantially as set forth.

8. The combination, with the circular revolving carrier-frame, of dies carried on radial and transverse shafts, substantially as set forth, and a guide arranged to present the nail-rod at an oblique angle to the frame and tangential to the path of the dies, as specified.

9. The combination, with the forming-dies

carried by the revolving frame, of a cutter-roller carrying a cutter-slide, and a roller having a cutting-edge, and appliances whereby the cutter is carried across the space between the rollers while the latter are turning backward, substantially as set forth.

10. In a nail-making machine, roller forming-dies arranged to operate on all sides of a stationary rod, and constructed to permit the rod to be admitted between them without contact except where it is desired to act thereon, substantially as set forth.

In testimony whereof I have signed my name to this specification in the presence of two subscribing witnesses.

ERASTUS E. PIERCE,

Witnesses:

WM. F. LLOYD,
BENJ. WILDE.
